PERCUSSION MUSICAL INSTRUMENT

Emil Carlson, Maspeth, N. Y.

Application June 14, 1950; Serial No. 168,054

4 Claims. (Cl. 84—405)

1

This invention relates to musical instruments, and more particularly to the xylophone type, which have been actuated heretofore by felted yarn or rubber hammers or mallets held in the hands of the musician.

The object of the invention is to provide a novel xylophone instrument in which hand-operated hammers need not be used, and in which the musical sounds are created by operating a keyboard which in turn, by electrical connections, actuates solenoids, the armatures of which strike the xylophone bars. This keyboard in one embodiment may be part of the cabinet in which the xylophone bars are encased, so that a self-contained musical instrument is provided, or the keyboard may be applied to another musical instrument, as an accordion, or a piano or organ, etc. to enable the percussion effect of the xylophone to accompany the musical composition being rendered by such accordion, piano or the like.

For this purpose, the invention consists of a plurality of superposed xylophone bars of progressively larger sizes, and a plurality of solenoids one for each xylophone bar arranged in progressively greater heights, to severally conform to the extending end of the xylophone bars. Electrical connections connect each key of the keyboard with each solenoid, so that as a key of the keyboard is depressed, a corresponding solenoid is actuated, which strikes its corresponding xylophone bar.

In the accompanying drawings,

Fig. 1 is a plan view of a xylophone instrument, without connections showing an open top for the dissemination of sounds;

Fig. 2 is a vertical section of Fig. 1, taken on line 2—2 of Fig. 1, with parts in side view;

Fig. 3 shows a keyboard on the top of the casing of Fig. 1, which may however, be remote on an accordion, piano or organ, or the like;

Fig. 4 is an electrical diagram of one unit, also showing an accordion connected in circuit;

Fig. 5 is a rear end view, with the rear wall removed;

Fig. 6 shows a plan view of the xylophone bars arranged on a partition having an opening; and

Fig. 7 shows an alternative mounting for supporting the xylophone bars.

Similar characters of reference indicate corresponding parts throughout the drawings.

Referring to the drawings, and more particularly to Fig. 1, a casing 10 has a rear opening 11, which is closed by a sliding door 12. Within the casing 10 there are disposed a plurality of horizontal partitions 15, the lateral sides of which fit into horizontal parallel slots 16, which may extend from front to rear of the casing, as the simplest form of mass manufacture, though each pair of slots, need only be the length of its corresponding partition. Each partition from the top partition to the lowest partition is progressively shorter. (Fig. 2.) Each partition supports two

2

suspension members 20, which preferably are made of a piece of covered wire or cord or cat gut, with their upper free ends 21 knotted or the like to prevent their passage through the hole 22 in the partition, and forming a U suspension passing through a bore 23, two in each xylophone bar 25. Each xylophone bar 25 is suspendingly balanced. The bores 23 are spaced from the ends of the xylophone to properly longitudinally balance the same, and the cord, wire or cat gut is adjusted to properly balance the xylophone bar transversely, so that the undersurface of the end 25a of the xylophone bar 25, presents a level surface that is in a horizontal plane. Below this end 25a which protrudes beyond the corresponding end of the xylophone bar next below, there is arranged a vertically disposed solenoid 30, the armature 31 of which has an upper surface 31a in a horizontal plane and parallel with the end surface 25a and spaced therefrom. The solenoid 30 is supported by a vertical tube 33, which has its lower end screwed to the horizontal bottom wall 34. Parallel with said tube 33 and solenoid 30, and horizontally spaced therefrom and shorter in vertical length, are a plurality of solenoids, and tubes. The tops of all of these solenoids form a step-like structure. (Fig. 2.)

Below the top xylophone bar 25 are a plurality of like xylophone bars supported by like partitions, as described, except for horizontal lengths, and the under surfaces of the ends of the xylophone bars are likewise in horizontal planes and hang over the ends of the corresponding solenoids.

By the arrangement described, a complete set of solenoids and their supports, based on the bottoms 34 and 34a suitably connected by an upright 34b, may be inserted in a casing 10, and thereafter, a complete set of xylophone bars are likewise installed therein, either separately or in a group entity, the latter by the horizontal partitions being secured to the movable wall 10a by individual brackets 15a.

Actuation of the solenoids, throws the respective armature upwardly, to strike against its mating xylophone bar. When the circuit is broken the armature will return by gravity to its lower inoperative position ready for its next actuation.

In the embodiment shown, five xylophone bars are arranged side by side (Fig. 1) in one horizontal tier, and eight vertical tiers are shown in Fig. 2, making forty xylophone bars with corresponding solenoids, the large number being made possible by the coacting step-like arrangement of the ends of the xylophone bars and solenoids.

The electrical connections are simple and a circuit is shown diagrammatically in Fig. 4. A circuit is composed of two supply conductors 40 and 41 connected with a transformer 42. A conductor 43 is connected with the end of the coil 44 of the solenoid, and a conductor 45 connected with the other end of the coil 44 and passes to microswitches 46, from which a conductor 47 returns to the transformer 42.

The current between conductors 43 and 47 passes to a switch 48 opened and closed by a switch action, when a key of the keyboard 49 (Fig. 3) or a key of the keyboard of the accordion 51 (Fig. 4) is depressed the circuit is closed, and when the key is released the circuit is opened. The microswitches 46 have a cam 45a, rotated as well known by a small motor (not shown) which cam makes and breaks the circuit with successive actions, so that the solenoids are set 10 into action in successive impellings in order that the xylophone bars are struck rapidly in succession to resemble the rapid repetitions of the mallet blows.

In Fig. 2, is shown the case 10 with the xylophone bars and solenoids therein, and with a cable 50, which includes all of the separate conductors, and which are operated by the keys of the keyboard. These individual keys, with their corresponding switches and conductors, are not 20 shown in multiple, as they are merely a duplication of the circuit shown in Fig. 4.

The xylophone bar supporting partitions may be all supported by a frame-work so that the entire xylophone bar group may be inserted as 25 a unit in the case, similar to the solenoid unit group, still permitting individual adjustment of the supporting partitions in the grooves of the case. An example, is shown in Fig. 2, where brackets 15a connect the partitions with the end 20 wall 10a.

In Fig. 2, the improved xylophone cabinet is shown connected by the cable 50, which may have its individual conductors connected with the key switches of either the keyboard 49 on the top 35 of the cabinet (Fig. 3), or connected with the keyboard of the accordion, or to a piano, organ, or the like. By the player of the accordion activating its keys 55, the corresponding xylophone bars are played in harmony with the accordion 40 sounds.

To prevent the partitions 15 from muffling the sounds of the xylophone bars, each partition is provided with an opening 15b, as shown in Fig. 6, as an example.

If it is desired to dispense with either the partitions in their individual form or as grouped together to form a group unit, as described, the xylophone bars may be provided with two spaced bores 23a, transversely of the bars, similar to the bores 23 described. A metal rod 55 is passed through the bores, and through the sidewalls 11 and 11a of the casing 10, transversely thereto. A spacer 56, preferably of rubber, is placed between each two adjacent bars. A locking collar 57 spaces each end bar from its adjacent casing wall. Each end of the rod 55 is threaded, and engaged by a removable nut 58. While Fig. 7 shows only one rod, it is to be understood, that a like structure, is spaced therefrom, these two rods occupying the relative positions corresponding to the bores 23 in Fig. 2. The bores 23a in the bars shown in Fig. 7 have a diameter larger than the diameters of the rods 55, to permit the vibration of the bars when actuated by the solenoids.

An amplifier 60 diagrammatically shown (Fig. 1) may be used to amplify the sounds. Details are known and are not shown.

The top wall 61 may be provided with an opening 62, covered by netting 63 to permit the passage of sound.

The armatures of the solenoids may be tipped with a fiber layer to soften the blows. Preferably, the armature 60a of the solenoids is supported by a cotton disk 61a, below which a light 75

coil spring 62a is placed, which rests on a felt washer or disk 63a. Projection 64 supports the washer 63a and is so placed to limit the movement of the armature 60a. In Fig. 3, each switch 48 is operated by one of the keys of the keyboard 51, and is placed adjacent such key, so that when the key is depressed, the switch is closed to energize the solenoid.

While the invention has never been described by the use of the word xylophone, it is clear that the invention includes like percussion instruments, as the marimba, vibraphone, bells, glockenspiel, etc.

Instead of mounting the xylophone bars in a horizontal plane as in the embodiment of this invention, the bars can be disposed in rotation horizontally to a set of vertical solenoids, or all the bars can be arranged vertically one above the other each in horizontal position with the solenoids vertically disposed.

I wish it to be understood that I do not desire to be limited to the exact details of construction shown and described, for obvious modifications will occur to a person skilled in the art.

I claim:

1. In a musical instrument, the combination of a casing, a plurality of suspended xylophone bars in the casing, in vertical alignment and of progressively increasing length from the lowermost to the uppermost with the inner ends portions arranged in stepped relation with one end portion of each bar extending beyond the adjacent end of the next lower bar, a solenoid associated with each of said bars and positioned in said casing with its armature adjacent the extending end of each bar in striking relationship thereto, so that energization of the solenoid will cause its armature to directly strike its bar, the adjacent ends of said bars to said armature being diagonal to said casing, a keyboard, and electrical means actuated by the keys of the keyboard to selectively energize said solenoids, thereby causing the armature of the selected solenoid to strike its associated bar directly.

2. In the structure of claim 1, in which the solenoids are arranged vertically in a self-contained group unit adapted to be inserted into the casing as a unitary body.

3. In the structure of claim 1, in which the solenoids are arranged vertically in a self-contained group unit adapted to be inserted into the casing as a unitary body, and the xylophone bars are arranged horizontally in a self-contained group unit adapted to be inserted into the casing as a unitary body.

4. In the structure of claim 1, said electrical means including a microswitch in circuit with the solenoid, and a motor driven cam, to operate the microswitch to vibrate the solenoid armature for striking the xylophone bar in roll characteristic.

EMIL CARLSON.
